UNITED STATES PATENT OFFICE.

ERROL M. THOMPSON, OF BROCKTON, MASSACHUSETTS, ASSIGNOR TO THOMPSON-
FIELD COMPANY, INC., OF BROCKTON, MASSACHUSETTS, A CORPORATION OF
MASSACHUSETTS.

SHOE-FILLER APPARATUS.

Continuation of application Serial No. 619,330, filed February 16, 1923. This application filed June 17, 1924. Serial No. 720,571.

To all whom it may concern:

Be it known that I, ERROL M. THOMPSON, a citizen of the United States, residing at Brockton, in the county of Plymouth and 5 State of Massachusetts, have invented a new and useful Improvement in Shoe-Filler Apparatus, of which the following is a specification.

10 My invention relates to a shoe filler apparatus designed for reducing shoe filler composition to a soft plastic condition suitable for application to shoe bottoms and for maintaining the filler in that condition while the apparatus is in use, and this application 15 is a continuation of a prior application filed by me Feb. 16, 1923, Serial No. 619,330, to the extent of the matter disclosed therein.

20 Heretofore, it has been customary to fill up the cavity in welt shoes between the inner and outer soles with a suitable material in order to give the sole of the shoe the requisite thickness and stability and the composition generally used for this purpose has been made up of comminuted leather or cork

25 held together by a suitable binder. It is desirable that the filler composition be resilient and pliable in the shoe, non-shifting after long use to prevent bunching up in the sole and that it be waterproof. As a rule, these

30 compositions when cold are semi-hard, but may be reduced to a plastic, moldable, and workable condition by the application of heat, and various apparatus have heretofore been devised for reducing the composition 35 to a plastic condition at the point where it is being applied to the shoes. The use of such apparatus, however, has heretofore been attended by certain objectionable features and disadvantages. Constant attend-

40 ance has been required to prevent the burning and charring of the filler material in contact with the sides of the receptacle, which burning or charring spoils the filler immediately affected and also discolors or 45 darkens the filler not burned. Frequently fire results from spontaneous combustion in case the apparatus is left unattended with the heat turned on for any appreciable length of time. The discoloration of the

50 filler due to the charring action of the apparatus is especially disadvantageous when light or tan shoes are being filled.

Furthermore, such apparatus have been open to the objection that it has required a

half hour or even longer period to reduce the 55 filler composition to a workable condition after the heat had been turned on in the apparatus. These disadvantageous features all tend to slow up and delay the filling operations and thereby increase the cost there- 60 of to the shoe manufacturers.

The principal object of my invention is the provision of an apparatus in which the shoe filler material is maintained in the proper plastic condition for application to 65 shoe bottoms and is free from any danger from injury or discoloration by burning or charring.

Another object of the invention is the provision of an apparatus so designed that the 70 semi-hard shoe filler composition is reduced to a suitable plastic condition for application within a very few minutes after the heat is turned on. A further object of the invention is the provision of an apparatus 75 which is simple and cheap in construction yet efficient in its operation.

Other objects of the invention will be more specifically set forth and described herein- 80 after.

One of the important features of my invention consists in making the filler receptacle of a soft metal having a high degree of conductivity, such for instance, as copper or aluminum. Heretofore, these receptacles 85 have been made of cast iron or steel, which requires a considerable period for heating, but which retains the heat to such a degree that the filler material in contact therewith is apt to be burned or charred. At the same 90 time this tendency to burning is somewhat increased by the fact that a comparatively high pressure of steam is used which is difficult to control. I have found, however, that by making the filler receptacle of alu- 95 minum or copper less heat is required for reducing and maintaining the filler in proper condition and all liability of burning and charring is obviated. The use of such a receptacle permits the machine to be 100 operated under a low steam pressure, a fact which is of considerable advantage to a shoe factory where it is generally difficult to get a high steam pressure without unusual expense.

Another important feature of my invention consists in providing a construction whereby live steam may be introduced di-

2
rectly into and through the shoe filler composition. I have found that the introduction of steam into the filler mass in this manner tends to reduce it quickly to a plastic condition when the machine is first started and also tends to prevent burning or discoloration of the filler. Care must be exercised, however, in the admission of the steam to the filler, because if too much is admitted, 10 the binder is thinned down to such an extent that its adhesiveness is affected and the filler material separates and rolls, interfering with its application to the shoes and later disintegrates in the soles, causing bunching 15 when the shoe is subjected to wear.

Sometimes an excess of steam will wash away the binder to such an extent that the cohesiveness of the filler is destroyed. For these reasons, therefore, it is important that 20 the amount of steam admitted to the filler be well distributed and limited in amount so that the reduction of the filler to a plastic condition may be rapidly accomplished without deleterious results to the binder. 25 I have found that the provision in the bottom of the filler chamber of a plurality of minute perforations spaced sufficiently far apart will accomplish the desired purpose.

In the embodiment of the invention here- 30 in illustrated, the apparatus comprises broadly a receptacle of suitable shape for reducing and maintaining the filler composition in a plastic condition, such receptacle being made of a soft metal such as 35 copper or aluminum. The receptacle may be heated either by the use of steam or electricity and in either case means are provided whereby live steam is introduced 40 through the perforated bottom of the receptacle into the filler mass.

In the drawings, Fig. 1 is a front elevation, a portion being broken away to show the interior construction, of an apparatus constructed and adapted to be operated in 45 accordance with my invention and provided with electrical heating means; Fig. 2 is a central sectional view of the same on line 2—2 in Fig. 1; Fig. 3 is a top plan view of the same looking downwardly in Fig. 1; Fig. 4 is a longitudinal vertical sectional view 50 of the roll and knife box and electrical heating unit for the same; Fig. 5 is a wiring diagram for the electrical heating means; Fig. 6 is a front elevation partly 55 in section of the device equipped with steam heating means; Fig. 7 is a central vertical sectional view of one form of knife box adapted for use when steam is employed as the heating medium; Fig. 8 is a detailed 60 sectional view of a portion of the steam chamber; and Fig. 9 is a detailed sectional view on an enlarged scale of a portion of the extended bottom of said receptacle.

65 Referring to the illustrated embodiment of the invention, 12 designates an open top

receptacle for containing the filler material to be treated, which receptacle may be of any suitable form, but preferably, especially on the front or operator's side 13, which may be made double, has sloping sides to 70 facilitate access to and handling of the filler composition. The receptacle may be made of any suitable material having a high degree of conductivity for heat, such as copper or aluminum, but I have found that a 75 receptacle cast from aluminum gives excellent results in that the filler may be reduced to plastic condition more rapidly and with less heat and is kept in better condition than when the receptacle is made of 80 other material, such as cast iron or steel. The bottom 14 of the receptacle may be provided with a threaded collar 16 adapted to receive the threaded upper end of a standard 18 for supporting it at the proper 85 height to suit the convenience of the operator.

On the inside just above the bottom 14 the receptacle may be provided with an inwardly extending flange 20 adapted to 90 support a plate 22 or false bottom which divides the receptacle into an upper open chamber 24 for containing filler and a lower closed steam chamber 26 which on the front 95 side 13 extends upwardly between the two walls thereof. The plate 22 may be removably secured to the flange by screws 28 in order to allow it to be easily taken out when necessary for cleaning or other purposes. 100

To permit steam to flow from the steam chamber 26 upwardly through the filler in the upper chamber, the plate 22 may be provided with a plurality of small perforations 30 spaced apart at suitable intervals 105 and cupped out at 31 on the under side of the plate (Fig. 9) to prevent clogging. The cupping out of the perforations reduces the length of the restricted passage to such an extent that any piece of cork or other matter in the filler small enough to enter the passage cannot remain there to obstruct it, but will fall through into the steam chamber. It is also desirable that the 110 perforations be spaced apart, because if too close together, so much steam is admitted to the filler that the binder is weakened and its adhesive qualities reduced thereby, making it difficult to handle with the spreading tools. 115

The receptacle may be heated either by steam or electricity. In case the former medium is employed, the steam chamber 26 may be provided at one side with an inlet 32 (Fig. 6) connected by a pipe 34 with a 120 source of supply controlled by a valve 36, and a by-pass pipe 38 connected to the supply pipe 34 may be carried up through a lug 37 over the receptacle and down the other side through a similar lug 39 for sup- 125

porting and heating by radiation a knife box 40 and an evening roll 42 mounted thereon over the receptacle. The pipe 38 may exhaust in any suitable manner, which exhaust may be controlled by a check valve 51. A valve 44 may be arranged in the supply pipe 34 between the by-pass and the steam chamber to allow the steam to be withheld from that chamber when necessary.

10 without affecting the heating of the roll and the knife box. An open drip pipe 35 may be located in the bottom 14 to permit the water of condensation to run out.

The knife box 40 (Fig. 7) is preferably made of a main center section, designated generally as 40 and being recessed on each side to form knife slots 46, when side portions 48 are secured thereto on each side by screws 50. When steam is used as the heating medium, the center portion 40 may be cored out and provided with alternately arranged baffle plates 52 to cause the steam to pass therethrough in a circuitous route and thereby to increase the temperature of the knife box. I have found this construction of knife box to be especially advantages when steam at low pressure is used and the box is made of cast iron, since difficulty has been experienced under such circumstances 30 in maintaining a solid box at a temperature sufficiently high to heat the spreading knives properly.

In the use of electricity as the heat supplying medium, two flat space heaters 60 of ordinary and well-known construction may be secured to the bottom 14 of the receptacle (Figs. 1 and 3) and a tubular space heater 62 may be mounted above the receptacle for heating the roll and knife box, said heaters being all included in one circuit, as shown in Fig. 5 in which 64, 66 and 68 designate the conductors connected to a source of electrical energy. A switch 70 of any suitable form of construction may be used for closing and opening the circuit. The switch and a pilot light 105 may be enclosed in a switch box 72 and the conductors in suitable flexible insulating tubing 74, 75 and 76 and in fixed tubing 77 and 78 (Fig. 51). The tubular space heater 62 may be conducted by screws 63 to conductors 64 and 66 and may be enclosed in a tubing 67 which carries the roll 42 and knife box 40 and is supported above the receptacle by means of two pairs of semi-circular flanged end plates 80 and 82, the plates in each pair being fastened together at their flanges by screws 84. The lower plate 82 of each pair is provided with a threaded opening to receive the threaded end of one of the fixed tubes 77 or 78. Set screws 83 prevent rotation of the tube 67 in the end plates and the knife box may be fixed on the heater 62 against rotation by a set screw 86. By means of this construction, the entire upper part of the

electrical heating means may be treated as a unit and in that condition removed from the apparatus when necessary by merely disconnecting the flexible tubing 75 and 76 therefrom and lifting it up to disengage the tubes 77 and 78 from the ears 37 and 39. At any time, however, access can be had to the space heater 62 by merely removing the upper end plates 80.

When the apparatus is equipped with electrical heating means, it is necessary to provide a small amount of water in the bottom of the receptacle from which steam may be generated and for this purpose the bottom 14 may be provided with an extension 90 having an upturned rim 91 and a closed water tank 92 may be pivotally secured by hinges 93 to the top of the receptacle above the extension. A nozzle 94 in that side of the tank which is normally the bottom side projects into the extension to within a short distance of the floor thereof to feed water from the tank when the level of the water falls below the mouth of the nozzle. The refilling of the tank is accomplished by turning it on the hinges 93 into the position shown in dotted lines in Fig. 2 and by removing the nozzle. A hole 95 permits water to flow from the extension into the steam chamber, said hole being closed by a screw plug 96 when the apparatus is used with steam. A plug 97 may be employed for closing the drip opening in the bottom 14.

In order that the current may be turned off when the tank is dry, I provide a switch 98 which is held normally open by an interior spring 99 and is mounted in a casing 100 secured by screws 101 to the rear wall of the receptacle and in position for the tank (Fig. 2) to engage the end of the plunger projecting from the casing. The switch is so arranged with respect to the tank that when the latter contains any appreciable amount of water it presses the switch 98 inwardly to close the circuit, but when it is comparatively empty, the spring 99 is of sufficient strength to overcome the lateral pressure exerted by the empty tank and to press the switch outwardly opening the circuit. This immediately shuts off the heat and in consequence gives notice to the operator that the tank needs replenishing.

In the operation of my apparatus, a suitable supply of the filler material is placed in the chamber 24 upon the perforated partition 22 and the heating medium whether steam or electricity is turned on, or if preferred the receptacle may first be heated and the filler then placed in the apparatus. The filler is more quickly reduced to a plastic workable condition when steam is employed as the heating medium, since it filters through the perforations in the partition and permeates the filler, softening the binder which is normally semi-hard. Preferably,

steam at a very low pressure is used and the flow of steam into the steam chamber may be regulated by the valve 44. When electricity is used, I find that placing the flat space heater on the under side of the bottom of the receptacle gives excellent results, although in starting it is somewhat slower than steam. After the apparatus has been started, the filler is maintained in plastic 10 and workable condition by the limited amount of steam which filters through the perforated partition. I have found that spacing the perforations approximately two inches apart gives most excellent results in 15 this respect and that the amount of steam admitted to the filler is sufficient to keep it in perfect workable condition without weakening the adhesive qualities of the binder.

In using the apparatus for filling shoes, 20 the operator takes his stand in front, with the shoe to be filled, sole up, in his left hand withdraws a hot knife from the knife box, scoops up the filler therewith and fills the bottom of the shoe, using the roll to even off 25 the same. The heating of the knife of the roll prevents the filler sticking to either. In doing this work, the operator generally moves the filler up against the front wall 13 of the receptacle where it may be conveniently 30 dipped out with the knife and the steam in between the double walls keeps the filler in proper condition and prevents cooling.

The apparatus of my invention has many advantages, some of which are directly due 35 to the fact that the receptacle is made of a metal having a high degree of conductivity for heat. Because of this quality, the machine is more rapid in its initial performance and the filler is ready for application 40 within a very few minutes after the heat is turned on. I have found when steam is used as the heating medium that the filler may be applied within two or three minutes. In case of electricity, this action is somewhat 45 slower, but still much faster than when a cast iron or steel receptacle is employed. Furthermore, the machine may be operated with less heat than is required for a cast iron or steel apparatus and is more efficient 50 and more economical. A steam pressure of but a few pounds will give satisfactory results and will conform more nearly to customary conditions in shoe factories where a high steam pressure involves expense.

55 With the use of my apparatus, all burning, charring, or discoloration of the filler is entirely obviated, although the filler is apparently more uniformly hot and plastic. The use of copper or aluminum avoids the 60 rusting or corrosion which is a common defect in iron or steel receptacles and which tends to discolor a light filler which is especially objectionable where light or tan shoes are being filled.

65 My machine may be very easily changed

from steam to electric heat or vice versa and therefore is adapted to be used under varying conditions.

Since, as hereinbefore stated, one of the important features of my invention consists 70 in spacing the perforations in the bottom of the filler material chamber sufficiently far apart to prevent the binder running or being drained from the filler material by an excess of steam vapor and a spacing of two 75 inches between perforations has been stated to give satisfactory results yet I do not wish to be limited to this spacing as otherwise than approximate. Undoubtedly, within certain 80 limits the perforations may be spaced nearer together or further apart than two inches, and this spacing may also vary with the amount of steam pressure used. For these reasons I do not desire to be limited 85 in the following claims to any specific dimensions for spacing the perforations except where specifically stated, since this feature of my invention is directed to any spacing which will admit only so much steam vapor to the filler material as will soften the binder 90 without causing it to run.

What I claim is:

1. A shoe filler apparatus having, in combination, a receptacle made from metal having a high degree of conductivity for heat, said receptacle having an upper chamber for holding the filler material and a lower steam chamber, a partition between said two chambers, said partition having perforations spaced approximately two 100 inches apart for admitting a limited amount of steam from said steam chamber to said filler, and means for heating said receptacle.

2. A shoe filler apparatus having, in combination, a receptacle made from a metal having a high degree of conductivity for heat such as copper or aluminum, said receptacle having an upper open chamber for the shoe filler material and a lower closed 110 chamber for steam, a partition between said two chambers provided with small perforations spaced approximately two inches apart for admitting a limited flow of steam from said steam chamber to said filler and means for providing steam to said steam chamber to heat said receptacle.

3. A shoe filler apparatus having, in combination, a receptacle cast from aluminum, a removable partition in said receptacle dividing it into an upper chamber for the filler material and a lower closed steam chamber, said partition being provided with a plurality of minute perforations for permitting a limited flow of steam from said steam chamber to said filler chamber, said perforations being spaced apart a distance sufficient to soften the binder but not to cause it to run, and means for providing steam for heating said receptacle and to 130

maintain the filler material in plastic condition.

4. A shoe filler apparatus having, in combination, a cast aluminum receptacle, a removable partition in said receptacle dividing it into an upper open chamber for the filler material and a lower closed steam chamber, said partition being provided with a plurality of minute perforations spaced apart for permitting a limited flow of steam from said steam chamber to said filler chamber, each of said perforations being cupped out to prevent clogging, and means for furnishing a supply of steam to said steam chamber to heat said receptacle and to maintain the filler in suitable plastic condition.
5. A shoe filler apparatus having, in combination, a receptacle, a removable partition in said receptacle dividing it into an upper open chamber for the filler material and a lower closed steam chamber, said partition being provided with a plurality of minute perforations for permitting a limited flow of steam from said steam chamber to said filler chamber, said perforations being spaced apart a distance sufficient to prevent the binder running, automatic means for supplying water to said steam chamber and electrical means for converting said water into steam to heat said receptacle and to maintain the filler in plastic condition.

6. A shoe filler apparatus having, in combination, a receptacle made of metal having a high degree of conductivity for heat such as copper or aluminum, a partition in said receptacle dividing it into an upper open chamber for the filler material and a lower closed steam chamber, said partition being provided with a plurality of minute perforations spaced apart for permitting a limited flow of steam from said steam chamber to said filler chamber, a tank for automatically supplying water to said steam chamber, electrical means for converting said water into steam to heat said receptacle and to maintain the filler in plastic condition and automatic operating means for shutting off the current in said electrical means whenever the water in said tank falls below a predetermined level.

7. A shoe filler apparatus having, in combination, a receptacle made of metal having a high degree of conductivity for heat such as copper or aluminum, a partition in said receptacle dividing it into an upper open chamber for the filler material and a lower closed steam chamber, said partition being provided with a plurality of minute

perforations spaced apart for permitting a limited flow of steam from said steam chamber to said filler chamber, a tank for automatically supplying water to said steam chamber, electrical space heaters mounted on the bottom of said receptacle, an electric circuit for operating said space heaters for converting said water into steam to heat said receptacle and a switch normally open for closing said circuit; said switch being arranged to be held open by said tank so long as the water in said tank remains above a predetermined level.

8. A shoe filler apparatus having, in combination, a receptacle for holding filler material, the bottom of said receptacle being provided with minute perforations for admitting steam vapor to the filler material therein and means for furnishing steam vapor to said receptacle through said perforations; said perforations being spaced apart a distance sufficient to prevent the running of the filler binder.

9. A shoe filler apparatus having, in combination, a receptacle for holding filler material, the bottom of said receptacle being provided with minute perforations for admitting steam vapor to the filler material therein and means for furnishing steam vapor to said receptacle through said perforations; said perforations being spaced approximately two inches apart to prevent the running of the filler binder.

10. A shoe filler apparatus, having in combination, a receptacle for holding filler material, the bottom of said receptacle being provided with minute cupped out perforations spaced apart for admitting steam vapor to the filler material therein, and means for furnishing steam vapor to said receptacle through said perforations.

11. A shoe filler apparatus having, in combination, a receptacle provided with a partition dividing it into an upper chamber for filler material and a lower steam chamber, said partition being provided with perforations for the passage of steam vapor from said steam chamber to said filler chamber to maintain said filler material in a workable condition, said perforations being spaced apart a distance sufficient to prevent the running of the filler binder, and means for furnishing steam vapor to said steam chamber.

In witness whereof, I hereunto set my hand this sixth day of June, 1924.

ERROL M. THOMPSON.
